ATTORNEYS

UNITED STATES PATENT OFFICE.

GEORGE BECKING, OF CHATTANOOGA, TENNESSEE.

DESIGN FOR A WATER-TANK CASING.

SPECIFICATION forming part of Design No. 32,923, dated July 10, 1900.

Application filed June 16, 1900. Serial No. 20,602. Term of patent 3½ years.

To all whom it may concern:

Be it known that I, GEORGE BECKING, a citizen of the United States, residing at Chattanooga, in the county of Hamilton and State of Tennessee, have invented and produced a new and original Design for a Water-Tank Casing, of which the following is a specification.

In the accompanying drawings, Figure 1 is a front view of my water-tank casing, and Fig. 2 is a horizontal section thereof.

The flat top of the casing has a projecting cornice *a*, whose edge is a species of ovolو molding, while its underside is provided with a row of pendent beads *b*. The projecting edge of the base *c* is rounded or convex. The

front of the casing has a central concave *d*, and rounded or convex corners *e*, extending vertically its entire length. The concave *d* and convexities *e* merge gradually into each other, thus presenting curves of large radius, producing lines of beauty and harmony impossible with pilasters or where the tank-case is made sectional. The back *f* is flat and vertical.

25

What I claim is—

The design for a water-tank casing as shown and described.

GEORGE BECKING.
